UNITED STATES PATENT OFFICE.

RANSOM H. HUSTED, OF TOPEKA, KANSAS.

WHEELED TOY.

Application filed March 1, 1926. Serial No. 91,533.

My invention relates to toys and has for its chief object; a simplicity of construction, being made of three separate pieces of wire.

A further object is to construct a toy having four wheels rotatably mounted on a chassis, the wheels and axle being made of a single piece of wire, and the wheels so constructed that a rubber tubing will slip over the felloe reaching the entire periphery and functioning as a rubber tire.

A still further object of my invention is to provide a miniature vehicle on which may be placed a bed at the discretion of the owner and also having means for coupling other similar vehicles.

A still further object of my invention is to provide a toy vehicle having a single spoke to each wheel for the convenience of bending at the hub point as a folding means, 20 economizing space for transportation.

A still further object of my invention is to provide a toy vehicle having an inexpensive propelling means that is replaceable without deterioration of the vehicle.

25 Referring to the drawings:

Fig. 1 is a side elevation of the vehicle.

Fig. 2 is a plan or top view of the device.

Fig. 3 is a perspective view of one pair of the wheels illustrating how the wheels 30 and axle are made from a single piece of wire.

The following is a more concise description in which, 1 is the chassis consisting of a coupling pole A which is formed by twisting the wires together, and on both ends thereof is formed the hounds B which laterally extend each way angling toward the central portion of the wheels, and having a bend as at C, from thence extending longitudinal with the chassis bending around the axle 2 as at D, and from thence outward to a bend E, then angling inward to a bend F, from thence running parallel with the axle thus forming a frame expanding 40 nearly the space between the wheels, but enough shorter to permit the rotation thereof without interference. It will be understood that the axles are trunnioned in the loops identified by D.

45 The chassis above described is formed from a single piece of wire by forming an eye 3 in the center thereof, and from thence having the plurality of bends as heretofore described, until the wires intersect as at G, 50 the wires then being twisted to the point as at H and spreading, following the bends

in duplicate of those on the opposite end. The parallel portion to the axle has an eye 4 formed by crossing the wires as at I, and twisting the ends together as at J, this being 60 the termination of both ends of the wire.

The wheels and axle are formed from a single piece of wire by bending a ring for the wheels as at 5, then by forming an abrupt bend as at K so that the wire extends 65 radially to the center of the ring as at L, at which point the axle 2 laterally extends to the wheel on the opposite end where the bends described are repeated and the members 7 functioning as spokes extend in 70 the opposite directions, thereby causing the wheels to balance. This manner of construction for the wheels will permit the sliding of a rubber tubing 8 on the (rings) or wheels functioning as a rubber tire.

75 When the vehicle is assembled I then attach a rubber band 9 in the eye 4 and to the opposite end of the elastic band I have attached a cord 10, said cord extending longitudinal and being tied in an eye 11, the said eye formed by looping the axle 2'. By taking hold of the axle with the thumb and finger it may be revolved thus winding the cord as shown by dotted lines 12, by which means the elastic band is stretched longitudinal until the end thereof is drawn near the axle as shown by dotted lines at M.

80 It is now readily seen that the tension of the elastic band will unwind the cord causing the wheels to rotate, the band being the motive power actuating a swift travel of the vehicle.

I do not confine the chassis being formed with the exact type of bends herein described as curvatures may be employed modifying the shape thereof: it will be further understood that the mechanism herein described is so designed that a bed as a container may be placed thereon, this being an inducement to cultivate mechanical skill among children, 95 and having an eye formed on both ends of the chassis is means for coupling a number of similar devices together as a train; therefore the device functions not only as a traveling toy, but is the base for further development.

100 Having thus described my invention, what I claim as new and desire to secure by Letters Patent is:—

110 In a wheeled toy, a twisted coupling pole terminating into a frame at each end thereof, an eye formed on each side of both of the

frames by a loop bend of its respective portion of the frame, a pair of wheels and an axle integrally connected by a right angle bend at each end of the axle, the right angle bends extending in opposite directions and radially positioned to their respective wheels, by which means said wheels are equally balanced, the axles trunnioned in the loops of

their respective frames, a rubber tubing as an enclosure for the rim of the wheel, an elastic means hitched to the outer portion of one of the frames, the opposite end attached to the axle trunnioned in the other frame. 10

RANSOM H. HUSTED.
